United States Patent Office.

WILLIAM SUTTON, OF WASHINGTON, GEORGIA.

Letters Patent No. 84,392, dated November 24, 1868.

IMPROVEMENT IN SAW COTTON-GIN.

The Schedule referred to in these Letters Patent and making part of the same.

To all whom it may concern:

Be it known that I, WILLIAM SUTTON, of Washington, in the county of Wilkes, and State of Georgia, have invented a new and improved Saw Cotton-Gin; and I do hereby declare that the following is a full, clear, and exact description thereof, which will enable those skilled in the art to make and use the same, reference being had to the accompanying drawings, forming part of this specification.

This invention relates to a new and useful improvement in the construction of hoppers for saw cotton-gins, whereby the cotton fed to the machine is acted upon equally throughout the entire gang of saws.

In the accompanying sheet of drawings—

Figure 1 is a front view of my invention.

Figure 2, a plan or top view of the same.

Figure 3, a transverse vertical section of the same, taken in the line *x x*, fig. 1.

Similar letters of reference indicate corresponding parts.

A represents the hopper of a saw cotton-gin, *B*, the bottom board, and *C*, the breast, composed of bars, *a*, placed at a suitable distance apart to admit of the saws, shown in red, working between them.

The hopper *A* has its end-pieces, *b b*, in an oblique position, or out of parallel with each other, so that in a forty-saw gin, the front of the hopper, *c c*, will be from two and a half to four inches narrower than its rear part, *d d*, which adjoins the body of the gin.

The proportions of hoppers will vary with size of gins. This is shown clearly in fig. 2, and in consequence of the width of the hopper not being uniform, the roll of cotton within the hopper is, when the gin is in operation, constantly shifting its position, so that fresh surfaces are constantly presented to the saws, and the cotton more rapidly ginned than usual, and the fibre not injured or cut.

The roll of cotton is also kept higher up in the hop-

per than usual, which admits of a free discharge of the seed, much more so than usual, and the saws operate with less friction, as the roll of cotton does not extend down so deep upon them.

In cotton-gins as heretofore constructed, the sides have been made straight, or parallel with the face of the saws. This construction is objectionable, from the fact that the spaces between the outer faces of the outer saws and the sides of the hopper are uniform, and very little if any cotton can find its way into them, because of the friction produced by its contact with the sides of the hopper. As a result of this construction, the outer saws of the gang do very little if any work.

By giving obliquity to the sides of the hopper, as I propose, the distance between the upper edges of the saws and the sides of the hopper is greater than the distance between the lower edges of the saws and the hopper, and therefore the cotton extending over the outer saws is readily acted upon and drawn downward.

The bars *a* of the breast *C* are curved, as shown in fig. 3, so as to admit of a comparatively large number of saw-teeth extending through the breast, but not so much of their surfaces or plates; for instance, the distance from *e* to *e* is about three inches greater than usual, while from *f* to *f* it is somewhat less. (See fig. 3.)

This change in the relative positions of the saws and breast also serves to retain the roll of cotton in an elevated state in the hopper, and to facilitate the operation of ginning in an eminent degree.

I claim as new, and desire to secure by Letters Patent—

The hopper *A*, constructed as described, with its sides inclined, for the purpose of supplying the cotton to all the saws equally, as herein shown and described.

WILLIAM SUTTON.
